UNITED STATES PATENT OFFICE.

EDWARD W. ROBINSON, OF SAVANNAH, GEORGIA, ASSIGNOR TO INTERNATIONAL BARREL COMPANY, OF SAVANNAH, GEORGIA, A CORPORATION OF GEORGIA.

HOOP-FORMING MACHINE.

1,192,562.

Specification of Letters Patent. Patented July 25, 1916.

Application filed June 18, 1915. Serial No. 34,855.

To all whom it may concern:

Be it known that I, EDWARD W. ROBINSON, a citizen of the United States, residing in Savannah, Georgia, have invented certain Improvements in Hoop-Forming Machines, of which the following is a specification.

My invention consists of certain improvements in the hoop forming machine constituting the subject of my application Serial No. 946, filed January 7, 1915, one object of my present invention being to bend a straight, flat strip of sheet metal or other material longitudinally into hoop form, and laterally so that it presents flanges at an angle to one another, one of said flanges having a hollow rib thereon, and a further object is to effect this result by a series of connected and continuous operations in one and the same machine. These objects I attain in the manner hereinafter set forth, reference being had to the accompanying drawings, in which—

Figure 1 is a perspective view illustrating the beginning of the operation of forming a hoop blank of the character described from a straight, flat strip; Fig. 2 is a side view of the machine whereby such operation is performed; Fig. 3 is an end view of the machine looking in the direction of the arrow, Fig. 2; Fig. 4 is a diagrammatic view of the shafts and gearing of the machine; Fig. 5 is a top view on a larger scale than Fig. 2 of a bending guide constituting one of the elements of said machine; Fig. 6 is an end view of the same looking in the direction of the arrows, Fig. 5, and Figs. 7, 8 and 9 are transverse sections of said bending guide, respectively, on lines *a—a*, *b—b*, and *c—c*, Fig. 5.

The strip from which the hoop is to be produced is, in the first instance, flat as shown at *x* in Fig. 1, and in passing through the machine has one of its edges gradually bent upward, as shown at *x'*, so that the strip, as it emerges from the machine, presents flanges *x²* and *x³* at a right angle to one another, the flange *x³* having thereon a hollow rib *x⁴*. The strip in its passage through the machine is also bent longitudinally, as shown in Fig. 1, consequently, if the strip is of sufficient length and is subjected to the action of the machine throughout such length the resultant effect will be the production of a split hoop with its ends

approaching or touching one another. The edgewise or longitudinal bending of the flange *x²* causes the formation therein of radial wrinkles or corrugations, as shown in Fig. 1, said wrinkles or corrugations increasing in size from the base to the edge of the flange.

The machine for producing a hoop blank of the character and by the method referred to has, as shown in Fig. 4, six positively driven shafts, numbered, respectively, 1, 2, 3, 4, 5 and 6, these shafts being driven one from another in the direction of their respective arrows, shown in Fig. 4, the shaft 1 constituting the main driving shaft and being geared to the shaft 2 by means of spur wheels *1^a* and *2^a*, the latter being mounted adjacent to the end of said shaft 2, as shown in Fig. 3.

The shaft 2 has a spur wheel *2^a* meshing with spur wheels *3^a* and *5^a* on the shafts 3 and 5, respectively, and said spur wheels *3^a* and *5^a* mesh with corresponding spur wheels *4^a* and *6^a* on the shafts 4 and 6, respectively. The shaft 6 is provided with a feed roll *6^b* which serves as a friction driver for a roll *7^b* on the shaft 7, the flat strip *x* passing in the first instance between these rolls *6^b* and *7^b* and said roll *7^b* having edge flanges *7^c* thereon which insure the passage of the strip in a straight course between the rolls.

The shafts 2 and 3 carry, respectively, rolls *2^b* and *3^b* which are retained in proper lateral relation to one another by means of a rib *2^c* on the roll *2^b* engaging with a groove *3^c* in the roll *3^b*, said roll *2^b* also having a rib *2^d* which enters a groove *3^d* in the roll *3^b*, as shown in Fig. 3.

The shaft 4 drives, by means of bevel wheels *4^b* and *8^a*, a vertical shaft 8 which is mounted in suitable bearings at the front of the machine, and is provided at its upper end with a horizontal roll *8^b* adjacent to the face of the roll *2^b*, as shown in Figs. 2 and 3, said bearing for the shaft 8 being preferably adjustable from and toward the face of the roll *3^b* by means of an adjusting screw *8^c*, as shown in Fig. 3, the range of adjustment not being sufficient to interfere with the proper meshing of the bevel wheels *4^d* and *8^a*.

Before passing between the rolls *2^b* and *3^b* the strip passes through a bending guide consisting of a block 10 having that end ad-

5 jacent to the rolls 2^b and 3^b concaved at top and bottom so as to project between said rolls almost up to the bite of the same, as shown in Fig. 2, the upper concave face of the block having therein grooves 10^c and 10^d, as shown in Fig. 5, for the reception, respectively, of the ribs 2^e and 2^d on the roll 2^b.

10 Extending longitudinally through the block 10 is a passage comprising a vertical member 11 and a horizontal member 14 joining said vertical member at the bottom of the same, as shown in Figs. 6 to 9, inclusive, one wall 12 of the member 11 of the passage being vertical and parallel with the longitudinal line of the block but the opposite wall 13 of said member 11 being parallel with the wall 12 only throughout its forward portion, and being thereafter inclined in respect to said wall 12 so that the member 11 of the 15 passage through the block tapers from the rear end of the block toward the forward end. The outer wall 13 of the passage member 11 is also inclined slightly in respect to the vertical from bottom to top, this inclination being greatest at the receiving end of the passage and gradually decreasing as it 20 approaches the delivery end.

Beyond the rolls 2^b are a pair of rollers 15 and 16, which overlap one another, the 30 roller 16 being below and in advance of the roller 15. The shafts of these rollers are adjustable forwardly and backwardly in slots 15^a and 16^a in a bearing plate 17 and should be provided with suitable means for 35 retaining them in proper longitudinal position after adjustment.

40 The strip x enters the passage through the block 10 in the direction of the arrow shown in Fig. 5, its right hand half occupying the member 14 of said passage and being vertically retained thereby and its left hand half lying on the bottom of the member 11 of the passage, which at the entrance is wide enough to permit this. As the strip 45 advances, however, in the direction of the arrow, Fig. 1, its left hand edge strikes the inclined wall 13 of the passage and is thereby bent upwardly, as shown in Figs. 7, 8 and 9, the strip as it leaves the forward end 50 of the block presenting two flanges x^2 and x^3 at a right angle to one another. The gradual bending up of the left hand half of the strip from the horizontal to the vertical position is represented at x' in Fig. 1, the 55 gradual change in the angle of this portion of the strip being represented by the gradual change in the angle of the shading lines applied thereto.

60 The flange x^3 of the strip passes between the rolls 2^b and 3^b, which thereafter serve to draw the strip through the block 10 and at the same time form the hollow rib x^4 on the flange x^3 by reason of the joint action of the rib 2^d of the roll 2^b and the groove 3^d of the roll 3^b. After the forward end of the strip

leaves the rolls 2^b and 3^b the flat portion of the flange x^3 is entered between the rolls 15 and 16, the emerging end of the strip being consequently compelled to turn upwardly owing to the fact that the bite of the rolls 15 and 16 is higher than that of the rolls 2^b and 3^b and the curvature thus imparted to the strip is continued throughout the entire rolling operation, so that the strip when it emerges from the machine is bent into hoop form.

70 The degree of curvature of the strip and consequently the diameter of the hoop blank to be produced may be varied by adjusting the rolls 15 and 16 from and toward the rolls 2^b and 3^b, the effect being that the nearer said rolls 15 and 16 are to the roll 2^b the less will be the diameter of the hoop and the farther said rolls 15 and 16 are away from the roll 2^b the greater will be its diameter. 75 While the strip is being subjected to the action of the rolls 2^b and 3^b its vertical flange is pressed toward the face of the roll 2^b by the horizontal roll 8^b, consequently there will be no deformation of said flange other than the slight buckling due to the edgewise bending of the same.

80 I claim:

1. In a machine for bending sheet metal strips, a block having therethrough a longitudinal passage presenting horizontal and vertical members communicating with one another at the angle, the horizontal member receiving approximately one half of the width of the strip and being of such dimensions as to vertically confine the same, and the vertical member receiving approximately the other half of the width of the strip and being of such dimensions as to permit upward bending of the same, said vertical member having one longitudinal wall parallel with the longitudinal line of the block and the opposite longitudinal wall inclined in respect thereto, whereby it gradually approaches the first wall from the 90 inlet end to the discharge end of the block, said longitudinally inclined wall being also vertically inclined at its inlet end but said inclination gradually diminishing until at the discharge end said wall is parallel with the vertical wall, in combination with means 95 for moving the sheet metal strip forwardly through said passage.

100 2: In a machine for bending sheet metal strips, a block having therethrough a longitudinal passage presenting horizontal and vertical members communicating with one another at the angle, the horizontal member receiving approximately one half of the width of the strip and being of such dimensions as to vertically confine the same, and the vertical member receiving approximately the other half of the width of the strip and being of such dimensions as to 105 permit upward bending of the same, said 110

vertical member having one longitudinal wall parallel with the longitudinal line of the block and the opposite longitudinal wall inclined in respect thereto, whereby it 5 gradually approaches the first wall from the inlet end to the discharge end of the block, in combination with a roll for drawing the sheet metal strip through the passage in the block and a side roll for pressing 10 upon the upturned flange of the strip, the delivery end of said block having therein a concave recess for receiving a portion of said draft roll and another concave recess at a right angle to that first mentioned for receiving a portion of the side presser roll.

3. In a machine for bending sheet metal strips, a block having therethrough a longitudinal passage presenting horizontal and vertical members communicating with one 20 another at the angle, the horizontal member receiving approximately one half of the width of the strip and being of such dimensions as to vertically confine the same, and the vertical member receiving approximately the other half of the width of the strip and being of such dimensions as to permit upward bending of the same, said vertical member having one longitudinal wall parallel with the longitudinal line 25 of the block and the opposite longitudinal wall inclined in respect thereto, whereby it gradually approaches the first wall from the inlet end to the discharge end of the block, in combination with a pair of rolls for drawing the sheet metal strip through the passage in the block and a side roll for pressing upon the upturned flange of the strip, the delivery end of said block having therein upper and lower concave recesses for receiving 35 portions of said draft rolls and another concave recess at a right angle to those first mentioned for receiving a portion of the side presser roll.

4. In a machine for bending sheet metal strips, a block having therethrough a longitudinal passage presenting horizontal and vertical members communicating with one another at the angle, the horizontal member receiving approximately one half of the 45 width of the strip and being of such dimensions as to vertically confine the same, and the vertical member receiving approxi-

mately the other half of the width of the strip and being of such dimensions as to permit upward bending of the same, said 55 vertical member having one longitudinal wall parallel with the longitudinal line of the block and the opposite longitudinal wall inclined in respect thereto, whereby it gradually approaches the first wall 60 from the inlet end to the discharge end of the block, in combination with a roll for drawing the sheet metal strip through the passage in the block, said roll having a convex rib thereon, and the delivery end of the 65 block having therein a concave recess for receiving a portion of said roll, said concave recess having therein a concave groove for receiving the convex rib on the roll.

5. In a machine for bending sheet metal strips, a block having therethrough a longitudinal passage presenting horizontal and vertical members communicating with one another at the angle, the horizontal member receiving approximately one half of the 75 width of the strip and being of such dimensions as to vertically confine the same, and the vertical member receiving approximately the other half of the width of the strip and being of such dimensions as to permit upward bending of the same, said vertical member having one longitudinal wall parallel with the longitudinal line of the block and the opposite longitudinal wall inclined in respect thereto, whereby it gradually approaches the first wall from the inlet 80 end to the discharge end of the block, in combination with a roll for drawing the sheet metal strip through the passage in the block, said roll having thereon a convex rib 85 and a square-faced rib, and the delivery end of the block having therein a concave recess for receiving a portion of said roll, which concave recess has therein a concave groove for receiving the convex rib of the 90 roll and a square-faced groove for receiving the square-faced rib of said roll.

In testimony whereof, I have signed my name to this specification in the presence of two subscribing witnesses.

EDWARD W. ROBINSON.
